UNITED STATES PATENT OFFICE.

FRED S. CARVER, OF NEWARK, NEW JERSEY.

COMPRESSION PUMP.

1,419,221.

Specification of Letters Patent. Patented June 13, 1922.

Application filed June 18, 1918. Serial No. 240,629.

To all whom it may concern:

Be it known that I, FRED S. CARVER, a citizen of the United States, and a resident of Newark, county of Essex, and State of New Jersey, have invented certain new and useful Improvements in Compression Pumps, of which the following is a specification.

My invention relates to pumps for compressing fluid, such as air. One important field for use of a high duty pump in accordance with the present invention is in the compression of air for filling pneumatic tires of motor vehicles. For example, many 10 of the heavy automobile trucks now used are equipped with pneumatic tires having a cross-sectional diameter as high as twelve inches or more and designed for carrying air pressures which may be as high as 150 15 pounds per square inch or even higher. A compression pump in accordance with my invention is well adapted for supplying air for filling such tires to the required high pressure, and is, of course, also adapted for 20 other uses where efficient compression of fluid, such as air, is desired.

With the foregoing and related objects in view, my invention consists in the parts, improvements, and combinations herein set 25 forth and claimed.

In the accompanying drawings in which the same reference numerals are uniformly applied to designate the same parts throughout, Figure 1 is a central, vertical, cross-sectional view of a pump embodying the invention, such sectional view being taken substantially on the line 1—1, Figure 2, and also on line A B E F of Figure 4. Figure 2 is an end view of the pump of Figure 1, 30 and Figure 3 is a side view thereof. Figure 4 is a transverse sectional view taken in the neighborhood of the upper end of the pump cylinders and substantially on the line 4—4, Figure 1. Figure 5 is a transverse sectional 35 view taken in the neighborhood of the lower end of the pump cylinders and substantially on the line 5—5, Figure 1. Figure 6 is a transverse sectional view taken on a plane beneath the lower ends of the pump 40 cylinders and substantially on line 6—6, Figure 1. Figure 7 is a vertical sectional view taken substantially on the broken line A B G H, Figure 4. Figure 8 is a vertical sectional view taken substantially on the 45 broken line A B C E F, Figure 4. Figure 9 is a vertical sectional view taken substantially on the broken line A B C D, Figure 4.

tially on the broken line A B C D, Figure 4. Figure 10 is a vertical sectional view taken substantially on the broken line A B G E F, Figure 4. Figure 11 is a detail sectional view of a preferred form of check valve on its seat, and Figure 12 is a plan view of the check valve shown in Figure 11.

The pump of the present invention is preferably of the type involving the use of a multiplicity of cylinders, the lower pressure cylinders discharging into the higher pressure cylinders. In the form shown a single low pressure and a single high pressure cylinder are illustrated, the low pressure cylinder being designated at 10 and the high pressure cylinder at 11. Such cylinders are preferably formed side by side in a block casting 12 by boring from the upper end thereof, leaving a substantially 70 plane upper surface as indicated at 13, the air passages being preferably suitably formed in the casting 12 as will hereinafter be described. The piston rods 14 and 15 of the pistons 16 and 17 project upwardly beyond the member 12. The pistons are preferably constructed of metal, as cast iron, and are provided with compression rings, as 16', 17'. A plurality of rings in separate 75 grooves may be provided as shown in Figures 7 to 10, or two or more rings may be placed in a single groove, as shown in Figure 1, or the rings may be arranged in other ways.

The drive mechanism is preferably located above the cylinders, and in the form shown a second block member, preferably a casting 18, is provided and is suitably secured to the member 12 as by a series of bolts 19 passing through flanges 20 and 21 95 on the members 18 and 12. A suitable gasket may be provided between the members 12 and 18, if desired, so as to secure an air-tight connection. Openings are provided in the lower wall 22 of the member 18 for the passage of the piston rods 14 and 15, and in the form shown upwardly extending bosses 23, 23 are provided for receiving openings 24, 25 for the piston rods, and suitable packing means are provided, in 100 the form shown oppositely tapered preferably metallic packing rings 26 being utilized and the same are secured in place as by means of screw rings 27, 27. The openings 24 and 25 in the bosses 23, 23, and the openings in the screw rings 27, 27, are preferably made sufficiently large to give fairly 110

substantial clearance about the piston rods so that the piston rods may have, to some extent, a floating action therein, the packing rings readily adjusting themselves thereto.

5 The driving means in the form shown comprises a shaft 28 carrying a cam or eccentric 29 which rotates in the preferably substantially elliptical opening 30 in a frame or Scotch yoke member 31 to which the piston rods 14 and 15 are firmly secured as by being screwed and pinned therein, such screw-threaded connection being indicated at 32, 32. The upper ends of the piston rods preferably have a driving fit in sockets provided therefor in the member 31 and may be forced in by being screwed home and permanently secured in place, as by pins or rivets, so that the machine part or element comprising the frame 31 and piston rods 14 10 and 15 forms a rigid substantially unitary structure which need never be taken apart and when worn to an extent requiring replacement, may be renewed as a whole. Said frame 31, which is adapted to be vertically reciprocated by the eccentric 29 and to impart vertically reciprocating movement to the pistons 16 and 17, is preferably provided with means for guiding and steadyng its movement in the casting or other member 15 20 25 30 35 40 45

18, and in the form shown such member 31 has laterally projecting shoulders 34, 34 formed thereon and with outer plane faces adapted to bear against and be guided by suitably formed and preferably opening 30 in the frame 31 is preferably elongated somewhat at the ends so as to give end clearance for the eccentric 29, as indicated in dotted lines in Figure 1, the working surface of the cam way being preferably in substantially short portions thereof at about its top and bottom portions. The working chamber in the member 18 is preferably filled with lubricating fluid, such as oil or the like, to substantially the line 38 (Fig. 1), and a filling plug 39 may be provided, the same also serving to limit the amount of oil which can be introduced, the oil being preferably put in the pump until it overflows at the plug opening 39. A drain plug may be provided for the oil chamber, if desired. It will be seen that all the working parts run in oil and that as the piston rods are raised to substantially the position corresponding with the dotted line 38 position of the frame 31 shown in the upper portion of Figure 1, they will be coated with oil, and the upper ends of the bearings for such piston rods in the bosses 23 are of course immersed in oil so that, particularly in the case of the low pressure cylinder and upon the suction stroke, more or less oil will gradually work into the pump cylinders from the oil bath in the casting 18. The pistons are double acting, admitting and compressing air at each end of the cylinders, and the air is compressed at each end of the low pressure cylinder, and is discharged to the opposite end of the high pressure cylinder. The air is further compressed in the high pressure cylinder. The control of the air in its passage through the pump is accomplished by six check valves arranged in the casting 12 and indicated, for identification, by Roman numerals I to VI.

Admission of air to the low pressure cylinder 10 is through the passage 40 controlled by the check valve I (Figure 7) to the upper end of such cylinder by the inlet 41. Air is admitted through the opening 42 formed partly in the screw-threaded plug 42' and controlled by the check valve III (Figure 9) to the lower end of such cylinder 10, which it enters by the inlet 43. Part of the passage 40 and the seat for the valve I are preferably formed in the casting 18 substantially as shown, but with this exception the passages and check valves are formed or located entirely within the casting 12. The inlets 40 and 42 may be formed directly in the casting wall and exposed to the outer air, but preferably they lead from the chamber 44, (Figure 5), which is formed by encircling the high pressure cylinder 11 with the cover 45 formed of sheet metal or the like, which may be suitably secured to the walls of the casting by screws 46. When such plate or cover is provided, openings such as the openings 47 are provided at a location adapted to obtain a sweep of the incoming air.

air past the walls of the high pressure cylinder 11 and to assist in cooling the same, the heat thus imparted to the incoming air being dissipated to a considerable extent by 5 the relatively extensive walls and surfaces of the low pressure cylinder 10, and in this way the heating up of the two cylinders in use may be equalized to a considerable extent, instead of being substantially or 10 largely confined to the high pressure cylinder, as might otherwise be the case. Air may thus be finally discharged from the pump at a considerably lower temperature than would otherwise be obtainable. The 15 cylinders or either of them may be provided with ribs or the like, if desired, to give additional exterior radiating and conducting surface.

The discharge of partially compressed 20 air from the upper end of the low pressure cylinder 10 into the lower end of the high pressure cylinder 11 is out through the port 41 (Figure 10) past the check valve I which remains seated, downward by the passage 48 25 and through the check valve II which is forced from its seat, and into the lower end of the high pressure cylinder 11 through the port 49. The passage of partially compressed air from the lower end of the low 30 pressure cylinder 10 is through the port 43 (Figure 8) past the check valve III which remains seated, upward through the passage 50, through the check valve IV which is forced from its seat, and into the upper end 35 of the cylinder 11 by the port 51.

The discharge of the compressed air from the upper end of the high pressure cylinder 11 is through the port 52 (Figure 1), downward through the passage 53, through the 40 check valve V and passage 54 into the hollow chamber 56 in the casting 12, the passage 54 being directed to discharge against the baffle plate 57. The discharge of compressed air from the lower end of the high 45 pressure cylinder 11 is out through the port 58 (Figure 1), through the check valve VI, through the passage 59, past the check valve V (which remains seated) and into the chamber 56 through the passage 54.

50 The compressed air is discharged through the port 60 on the other side of the downwardly extending wall or baffle plate 57, through the hose connection 61 to which the flexible hose 62 is secured leading to the 55 tire or other device into which the air is to be pumped.

It will be seen that each end of the high 60 pressure cylinder contains two ports, one to the air discharge and one leading in from the opposite end of the low pressure cylinder, those for the upper end of the high pressure cylinder being numbered 51 and 52 (Figures 1 and 8), and for the lower ends 65 49 and 58 (Figures 1 and 10). Accordingly when the back pressure in the passages lead-

ing to the hose 62 is low, as during the early stages of pumping up a tire, large volumes of air may be pumped in substantially directly by the low pressure cylinder 10, the air passing momentarily into the high pressure cylinder through passages 51 and 49, respectively, (Figures 8 and 10) and immediately out through the passages 52 and 58, respectively, (Figure 1). When the back pressure increases, however, the pressure 75 from the cylinder 10 is no longer sufficient to open the check valves V and VI and all the air partially compressed in the low pressure cylinder is recompressed in the cylinder 11 before discharge. 80

The check valves are preferably all of substantially identical construction and may comprise a perforated disk 70, preferably of material such as fibre, with preferably identical longitudinally extending guide members on each side thereof and between which the disk is interposed. In the form shown, one of such members 71 has a stem 71' thereon extending through the opening 72 in the fibre disk 70 and passing through a central 90 longitudinal bore in the member 73, which is preferably substantially identical with the member 70, except for the fact of its being provided with a bore instead of the stem 71'. The parts are secured together preferably 95 by riveting over the stem 71' to form a head 74. Formed in this or equivalent ways, the two sides of the valve are substantially identical and the valve may be inserted interchangeably and with either of the faces of 100 the disk 70 thereof in contact with a valve seat as 75, (Figure 11). Springs 76 are preferably provided to encircle the guide member of the valve opposite the seat, and the same are preferably received in recesses 105 such as shown at 77. The material of the members 70 and 73 is preferably cut away at the sides to permit the free passage of air therearound. In Figure 12 such valve members are shown provided with three arcuate 110 cut-outs 78, whereas in the other figures of the drawings in which the check valves appear, they are shown as having cut-outs on four sides, but it will, of course, be apparent that considerable variation in this respect 115 is possible. Check valves constructed as described operate efficiently with little noise and cannot readily stick or bind, and operate well even if the springs therefor should be broken. 120

It is desirable that oil be prevented from being discharged with the air, particularly into rubber tires which may be injured thereby, and means are provided for preventing the oil being carried along by the 125 air at least to a harmful extent. In the form shown an oil well 63 is provided which is preferably substantially an extension of the chamber 56, and the air is driven around the dead wall or baffle plate 57 whereby an effi- 130

cient separating action is obtained between the oil and the air, and the former is collected in the well 63 which, in the form shown, is provided within a removable bowl or the 5 like 64 adapted to be firmly held in place as by means of a screw 66 screwed into an opening in the dead wall 57.

Means for draining the well 63 are provided, since if the oil collected in such well 10 rises to an unduly great height, it will be carried over with the air discharged from the pump. In the form shown such means for discharging surplus oil is combined with means for testing the operation of the pump 15 and enabling the operator to determine whether it is working well. Such means, in the embodiment shown, takes the form of a screw drain cock 65 clearly illustrated in Figures 2 and 3, and it will be seen that 20 upon opening said drain cock, as by unscrewing it, the oil may be permitted to be discharged through a suitable drain opening 65^a, being driven out by escaping air. Since, in the case of the use of a pump on trucks for 25 inflating large tires, the chauffeur or mechanic has substantially nothing to do while the inflation is going on, it will be easy for him to open the drain cock 65 occasionally, which he will also be inclined to do as it 30 affords a test for indicating how the pump is working. If such drain cock is opened for a few seconds in the course of inflation of three or four tires, it will be ordinarily sufficient for securing the discharge of 35 surplus oil and preventing the discharge of any substantial quantity of oil with the compressed air.

It will be seen that a compression pump in accordance with the present invention embodies numerous features of advantage. It 40 is simply constructed and readily assembled, is compact and low down and can be attached to operating means, such as automobile or truck engines, in convenient fashion, 45 the drive shaft 28 being preferably made reversible so that it may project from either side. Also it may be conveniently secured in place in a variety of different positions, as, for example, by means of suitable fastening bolts entering threaded holes 67, 67, 50 provided in duplicate on opposite sides of the pump, the material whereof is preferably suitably thickened about such openings, as indicated at 68, in order to provide the necessary strength. Lubrication is cared for in 55 an extremely efficient manner, all the working parts being constantly run in a bath of oil, and the parts being so arranged and constructed as that the oil in said bath gradually enters the pump cylinders, keeping the 60 same thoroughly lubricated and excessive oil may be disposed of with ease by means of the drain cock 65 being open for a short interval, and various other advantages are secured, as 65 will be apparent from the foregoing de-

scription. It is to be understood that the embodiment illustrated is intended only for the purpose of affording a clear understanding of my invention and that I am not to be limited thereby, but that my invention is of 70 the scope defined by my claims.

I claim:

1. A compound double acting compression pump comprising a combination of high and low pressure cylinders, arranged 75 side by side in a single casting, with separate axes parallel to one another, and double acting pistons therein with but six check valves for controlling the passage of fluid.

2. The combination in a pump of an oil 80 separator, a pump cylinder and its piston, and an oil reservoir arranged respectively one above another, the reservoir being arranged to feed oil to the cylinder, and the separator being adapted to separate oil from 85 compressed air discharged from the cylinder.

3. The combination in a pump of an oil separator, a cylinder with its piston and upwardly projecting piston rod, and an oil 90 chamber into which the piston projects and having means for actuating the piston, the separator, cylinder and chamber being arranged respectively one above another and providing a relatively high device of relatively small horizontal section and adapted 95 to be secured to and operated from an internal combustion engine.

4. In a pump, the combination of a cylinder, a piston and a piston rod therefor, packing means for said piston rod, a chamber above the cylinder and into which said piston rod projects, said chamber being adapted to contain an oil bath, and means enclosed within said chamber for imparting a 100 reciprocatory movement to said piston rod and piston.

5. In a compression pump, the combination of a cylinder, a piston therein and a piston rod projecting upwardly from the 110 cylinder, packing means for the piston rod, a chamber into which said piston rod projects and adapted to contain an oil bath, means enclosed in said chamber for imparting reciprocatory movement to the piston rod and piston, whereby oil is introduced 115 into the cylinder from said chamber, and means beneath the cylinder for separating oil from compressed fluid discharged from the pump.

6. In a compression pump, the combination of a plurality of cylinders arranged side by side and comprising a low pressure and a high pressure cylinder, pistons in said cylinders and piston rods projecting therefrom, packing means for said piston rods, said piston rods and packing means being mounted to substantially float in their bearings, a chamber above said cylinders adapted to contain an oil bath, a Scotch yoke in 125 130

said chamber, a rotating cam adapted to impart reciprocatory movement to said Scotch yoke and pistons, said Scotch yoke having side shoulder members extending 5 low down thereon and substantially closely adjacent to the cylinders, and guide-ways for said shoulders formed in the walls of said chamber.

7. In a compression pump, the combination of a cylinder, a piston therein and a piston rod projecting upwardly therefrom, packing means above said cylinder in which said piston rod is adapted to substantially float, a chamber above the cylinder into 15 which the piston rod projects and adapted to contain an oil bath, means for imparting reciprocatory movement to said piston rod, and guide means therefor located on opposite sides of the upwardly projecting ends 20 of the piston rod.

8. In a compression pump, the combination of a casting having an open-ended cylindrical bore formed therein and provided with a piston and piston rod, a second casting adapted to be secured upon the first named casting and having packing means about the piston rod in its lower wall and adapted to contain an oil bath, a third casting arranged on top of the second casting, 25 the last two named castings forming an enclosed chamber, and means in said chamber for imparting reciprocatory movement to said piston.

9. In a compression pump, the combination of three castings placed successively on top of one another and secured together, the lower casting containing cylinders and pistons moving therein, piston rods for said pistons projecting into the middle casting, 40 said middle casting being adapted to contain an oil bath and the top casting forming a cover therefor, and rotatable means having bearings between the second and third castings and adapted to impart reciprocatory movement to the piston rods.

10. In a compression pump, the combination of a bottom casting having cylinder bores formed therein and open at their upper ends, pistons in said cylinders and having piston rods projecting upwardly therefrom, a second casting arranged upon the first casting and closing the open ends of the cylinders except that passages are provided for the pistons having packing means 55 therein, said casting being adapted to contain an oil bath and providing an enclosed chamber, means in said casting for imparting reciprocatory movement to said pistons, and guiding means for said movement imparting means located within the second named casting and substantially closely adjacent to the upper ends of said cylinders.

11. In an air compression pump, the combination of a high pressure cylinder and a 60 low pressure cylinder, and means whereby

the air admitted to the low pressure cylinder is utilized to cool the high pressure cylinder.

12. In an air compression pump, the combination of high pressure and low pressure 70 cylinders, and means whereby the air admitted to a low pressure cylinder is caused to pass over the walls of a high pressure cylinder before admission to a low pressure cylinder. 75

13. In an air compression pump, the combination of high and low pressure cylinders, an enclosure about a high pressure cylinder, and means for admitting air into and through said enclosure to a low pressure cylinder, whereby the walls of the high pressure cylinder are cooled by the air admitted to the low pressure cylinder. 80

14. In an air compression pump, the combination of a high pressure cylinder and a 85 low pressure cylinder, and a sheet metal covering for the high pressure cylinder provided with air inlet openings, the inlets of the low pressure cylinder being arranged within said shell and adapted to cause the 90 air incoming to the low pressure cylinder to sweep past the walls of the high pressure cylinder and assist in cooling same.

15. In a compound pump comprising a low pressure cylinder and a high pressure 95 cylinder into which air is received from the low pressure cylinder and further compressed, an oil chamber over both cylinders and into which their piston rods project, whereby oil is carried into the low pressure cylinder only on its suction stroke, said oil passing with the air into and through the high pressure cylinder, and means for separating oil from discharged air after leaving the high pressure cylinder. 100 105

16. In a compound double acting pump, the combination of a casting having high pressure and low pressure cylinders therein side by side, double acting pistons in said cylinders adapted to move together, said casting being provided with passages formed therein connecting opposite ends of the low pressure and high pressure cylinders, and check valves in said passages, an air admission passage leading into each of the first 110 named passages, and check valves for said air admission passages. 115

17. In an air pump, the combination with a casting having a low pressure cylinder and a high pressure cylinder formed therein and disposed side by side, a double acting piston in each cylinder, each of said cylinders being provided at each end with a port, and passages formed substantially entirely in said casting and connecting the ports at the 120 respective ends of the low pressure cylinder with the ports at the opposite ends of the high pressure cylinder, an air admission passage leading into each of the first named 125 passages, outwardly closing check valves for 130

the air admission passages, and outwardly opening check valves for the first named passages.

18. In a pump a cylinder, an oil chamber thereover, a piston in the cylinder and having a piston rod extending into the body of the oil in said chamber whereby oil is carried into the cylinder by the piston rod for lubricating the same, and means for separating the oil from compressed air discharged from said cylinder.

19. In a compression pump, an oil chamber, a cross head and actuating means therefor in said chamber, high and low pressure pistons on the same side of said cross head

and arranged for lubrication from the oil in said chamber.

20. In a compression pump, an oil chamber, a cross head and reciprocating means therefor in said chamber a pair of cylinders, 20 a wall separating said cylinders from said chamber, pistons in said cylinders and having piston rods extending through said wall, and packing means in said wall for said piston rods.

25 In testimony that I claim the foregoing, I hereto set my hand, this 13th day of June, 1918.

FRED S. CARVER.
